Primary Examiner — Wendy L Arminio(74) *Attorney, Agent, or Firm* — Aronberg Goldgehn Davis & Garmisa(57) **CLAIM**

The ornamental design for a water bottle, as shown and described.

DESCRIPTION

FIG. 1 is a front elevation view of a water bottle of the instant inventive concept.

FIG. 2 is a rear elevation view of the water bottle of FIG. 1.

FIG. 3 is a left side elevation view of the water bottle of FIG. 1.

FIG. 4 is a right side elevation view of the water bottle of FIG. 1.

FIG. 5 is a bottom plan view of the water bottle of FIG. 1; and,

FIG. 6 is a top plan view of the water bottle of FIG. 1. The broken lines in the drawings of the water bottle illustrate the portions of the water bottle that form no part of the claimed design.
